UNITED STATES PATENT OFFICE.

THOMAS GALLOWAY, OF SUPERIOR, WISCONSIN.

MECHANICAL HOIST.

Application filed February 23, 1923. Serial No. 620,581.

To all whom it may concern:

Be it known that I, THOMAS GALLOWAY, a citizen of the United States, residing at Superior, in the county of Douglas and

5 State of Wisconsin, have invented certain new and useful Improvements in Mechanical Hoists, of which the following is a specification, reference being had therein to the accompanying drawing.

10 This invention relates to mechanical hoists and has special reference to a double drum line hoist for use in the art of mining, where what is commonly known as "slushing" is practiced, that is to say where the mucking in a tunnel is accomplished by scraping the muck from the face of the tunnel to a rise or chute, the drag or scraper being operated in both directions by a single line.

15 The principal object of the invention is 20 that of producing as simple and efficient a device for the purpose as possible.

Other objects and advantages of the invention will appear in the further description thereof.

25 Referring to the accompanying drawing forming part of this application in which like reference characters indicate like parts:

Figure 1 is a top plan view, partly in section, of the complete hoisting unit:

30 Figure 2 is an elevation of the inner face of one of the hoisting drums:

Figure 3 is an end elevation of the drum farthest from the motor of the hoist showing specifically the arrangement of brakes therefor:

35 Figure 4 is a combined elevation and section of a modification of the intermittent clutch for the drum: and

Figure 5 is an elevation of the clutch head illustrated in Figure 1.

The entire hoisting elements are securely assembled upon a single metal base 1. 2 represents an electric motor, furnishing the power of the hoist, the same being a reversible type of motor the controller of which is illustrated at 3. 4 represents the armature shaft of the motor which carries the spur gear 5 meshing with the larger spur gear 6 mounted upon a short counter-shaft 7, the bearing for said shaft appearing at 8, which may be integral with the base 1 or removably mounted thereupon as desired; the same applying to the bearings 10 and 11 for the drum shaft 9.

55 A smaller spur gear 12 is mounted upon the opposite end of the shaft 7 and meshes

with the annular gear wheel 13 which is securely keyed to the drum shaft 9 and provides rotation therefor.

Loosely mounted upon the drum shaft 9 are the line winding drums 14 and 15, they being alike in shape and diameter and preferably provided intermediate of the ends of the hub portions with a felt lubricant absorbing washer 16 for the insurance of good lubrication. Each of these drums has a head portion 17 which is provided with an annular band brake or flange 18 which operate in close juxtaposition when the drums are properly assembled upon the shaft 9. Intermediate of the heads 17 of the drums and in the space housed by the band brake flanges is securely fixed to the shaft 9 the driving head 19, it being somewhat in the shape of a crank arm carrying upon its free end 20 a horizontally reciprocable dog 21. This dog is for intermittent engagement with first one drum and then the other and for such engagement the drum heads are each provided with a series of spaced lugs 22. However the lugs on one drum face in one direction while the lugs on the other drum face in the opposite direction, they each having a flat radially disposed dog engaging face. The free end 20 of the driving head 19 is of a width to just nicely clear the projecting lugs 22, and the dog 21 is approximately the depth of one lug greater in length than the width of the end 20 of the working head so that it normally engages either one set of lugs or the other when in action. The dog 21 is normally held in position to engage the lugs on either one drum or the other by means of a radially reciprocable key 23 which is circular in form having a conically shaped upper end which fits within either one or the other of the two notches 24 formed in the lower edge of the dog 21; the key being normally held outwardly by suitable expansive spring 25 upon which it rests. This key, it will be understood, does not permanently prevent the reciprocation of the dog.

From the foregoing it is evident that when the driving head is rotated in either direction it will be engaged by the inclined outer body portion of one set of lugs and forced away from same into engagement with the opposite set of lugs, which engagement will be augmented and insured by the key having access to one or the other of the notches 24 thus normally holding in driving engage-

ment the drum carrying the lugs contacted, so that when the working head is rotated in one direction it will carry with it one of the drums and permit the other one to operate freely upon the shaft 9; while when driven in the opposite direction the other drum will be engaged and the previously engaged one freed to rotate at will upon the shaft. This, as is obvious, will necessitate the line 26 being wound upon opposite sides of the two drums, that is the line on one drum will be overshot and the line on the other drum undershot, so that as one winds up the other is free to unwind.

15 As a means for controlling the rotation of particularly the free drum, a brake band shaft 27 is installed parallel with the shaft 9 and somewhat below same adjacent the outer circumferential flange of the drums, said shaft being journaled in the bearing 28 at one end and in the extension 29 of the bearing 11 at the other end and said shaft extends slightly beyond the side extremity of the base 1 where it carries rigidly 25 fixed thereto the upstanding operating lever 30. This lever is designed to be positioned in convenient access to an operator adjacent the controller.

At the opposite end of the shaft 27 are 30 rigidly mounted two double spaced crank arms, the hubs of which are indicated at 31 and 32, each hub having a horizontally projecting arm 33 and a downwardly extending vertical arm 34, and thru each pair 35 of arms thus spaced is mounted a pin 35 to which one end of each of the band brakes 36 and 37 is attached, for example, one end of the band 36 fastened to the pin 35 between the arms 33 the opposite end of said 40 band being attached about the shaft 27, while one end of the band 37 is attached to the pin 35 in the arm 34 and its opposite end is attached to the shaft 27, so that when the hand lever 30 is moved in one direction, 45 thus rotating the shaft 27, one band will be applied and the other released. When said lever is forced in the opposite direction, the formerly tightened band will be released and the other tightened, or when the lever 50 is allowed to remain in vertical or neutral position, both bands will be slack.

In this manner it becomes possible when winding up on either drum to apply the

brake to the opposite drum to prevent its 55 unwinding too rapidly.

In the modified form of clutch shown in Figure 4, I have simply illustrated a collar or clutch member 38 which is splined upon the shaft 9, the same having a series of teeth on the opposite faces thereof extending in 60 opposite directions so that when the clutch is rotated by the action of the shaft 9 it will carry with it the drum 39 having teeth which cooperatively lockingly engage with the clutch, as when the clutch touches teeth 65 normally tending to become disengaged with the clutch they will tend to force it longitudinally on the shaft for engagement with the teeth on the drum which register therewith.

From the foregoing it is evident that I have devised a very simple, compact and practical double drum hoist, admirably adapted for the purpose intended, and though I have specifically referred to its being used for 75 mining purposes it is evident that the same may be adapted to other uses.

Having thus described my invention, what I claim and desire to secure by Letters Patent, is:

1. In combination, a rotatable shaft, a radially disposed driving head rigidly fixed to the shaft, winding drums loosely mounted upon the shaft, one upon either side of the driving head, and a reciprocable dog mounted in the free end of the driving head 85 remote from the shaft for alternate engagement with the drums to rotate them in opposite directions.

2. In combination, a rotatable shaft, a radially disposed driving head rigidly fixed to the shaft, winding drums loosely mounted upon the shaft, one upon either side of the driving head, a reciprocable dog mounted in the free end of the driving head remote 95 from the shaft for alternate engagement with the drums to rotate them in opposite directions, and spring controlled means for holding the dog in either of its driving positions.

In testimony whereof I hereunto affix my signature in the presence of two witnesses.

THOMAS GALLOWAY.
